ATTORNEY

UNITED STATES PATENT OFFICE

WILLIAM CALVANO, OF NEW YORK, N. Y.

STAMP MAGAZINE

Application filed January 8, 1929. Serial No. 331,134.

This invention relates to a device for carrying stamps.

One object of the invention is to provide a stamp carrying device which is capable of being attached to the end of a pencil, lip stick, or the like.

A further object of the invention is to provide a stamp carrying magazine in which the stamps are carried on a spindle rotatably mounted within a casing having a slot through which the stamps may be withdrawn.

Another object of the invention is to provide a stamp carrying magazine which has few separate parts and which can easily be put together.

In accordance with my invention the device comprises a casing with a slot therein and a spindle rotatably mounted in said casing to which spindle is attached a strip of waxed cloth or paper, or other suitable material. This strip is of the width of a stamp and is cut at its outer end to form a narrow lead strip. To this strip is attached a device which is adapted to flip out of the cylinder when it reaches the slot. The spindle may be made in the form of a spool, both ends of said spool being of substantially the internal diameter of the casing. The spindle may also be made so that one end of it is adapted to fit into a hole in a bearing plate in the casing. The entire device may be detachably or permanently fitted onto the end of a pencil, lip stick or the like, or can be used alone. An eraser may also be attached to the outer end of the spindle.

I shall now describe my invention in detail, reference being had to the accompanying drawings.

Fig. 1 is a side elevation of the cylinder with the spindle attached.

Fig. 2 is a longitudinal sectional view of the device shown in Fig. 1.

Fig. 3 shows the stamp carrying strip with the lead strip formed at the end of it, and the device adapted to flip out of the slot attached to said strip.

Fig. 4 is a sectional view of the device taken along the lines 4-4 of Fig. 1.

Fig. 5 shows an alternative method of attaching the spindle to the cylinder.

Fig. 6 shows a modification in which a spring is used to return the stamp to the cylinder.

Fig. 7 is a sectional view of the device of Fig. 6 taken along lines 7-7.

Referring particularly to Fig. 1, reference numeral 1 is the cylinder into which fits the spindle 2; 3 is the slot through which the stamps can be withdrawn. In the center of the slot 3 is cut a depression 4 through which the end of the lead strip may flip out. The end of the cylinder is provided with a slit 5 so that the cylinder can be removably and tightly fastened to a pencil or the like.

In Fig. 2 there is shown a method of rotatably fastening the spindle 2 in the cylinder 1. The spindle 2 consists of the head 13, the bar 6 and an end piece 8. A depression 9 is made in the outside wall of the cylinder at such a distance from the head that the end piece 8 of the spindle will rest just on the far side of it when the spindle is pushed home. The end piece 8 is forced past this depression and the spindle will then be fixed in the cylinder so that it cannot come out unless it is pulled. A slit 7 is made in the bar 6 of the same length as the width of the strip of waxed cloth or paper which is used. The strip of paper or cloth is then fitted in the said slit and wound on the spindle. An eraser 10 may be attached to the head 13 of the spindle 2 by forcing it into a hole which is provided therein.

In Fig. 3 the strip of waxed paper or cloth or other suitable material is shown at 18, and the lead strip is shown at 17. Attached to the outer end of the lead strip 17 is a piece of springy material 14 such as fibre or thin metal. This is made at its end with a slight opposite curvature to that of the cylinder. At 15 there is a jog in the piece 14. This jog is designed to engage with the edge of the slot 3 and is useful because the strip 18 being tightly wound might pull the end 14 of the strip back into the cylinder if there were nothing to stop it.

The spindle could also be fixed in the cylinder, as shown in Fig. 5, where 12 represents an annular plate attached to the inside of the cylinder 1. In the middle of this plate is a

hole, the internal diameter of which is substantially the same as that of the bar 6. The end 11 of the bar 6 is of slightly larger diameter than that of the rest of the bar and is 5 provided with a small slit 25 so that it may be compressed as it is forced through the hole in the plate 12. Once the end of the spindle is forced through the hole it will remain fixed in the cylinder and will not be able to fall out.

10 In Fig. 6 is shown the spring 20 which is used to return the strip to the cylinder when it has been pulled out. This spring is attached at one end to a plate 21 which itself is fixedly attached to the bar 6, and the spring is 15 attached at its other end to a bearing plate 22 on the bar 6, said bearing plate being held on the bar by means of a protuberance 23. A depression 19 is formed on the outside wall of the casing and a corresponding depression 24 is formed in the bearing plate 22. The spindle is held against longitudinal motion in the casing by means of depressions 24 in the casing and corresponding depressions in that part of the head 13 which is inside the casing. 25

If desirable the lead strip may be printed with advertising matter which will come into view as the strip is withdrawn during use of the device. The strip may, if desirable, be 30 made of oiled silk or starched linen, such as tracing cloth used in drafting, and may or may not be made narrow at the end. If the strip is not made narrow at the end, but left square, the opening in the magazine casing 35 may be a single narrow slit.

While I have described a particular embodiment of my invention for the purposes of illustration, it will be understood that the invention is capable of various modifications and adaptations and is to be limited only by the scope of the appended claims. 40

What I claim is:

1. In a stamp magazine, a tubular casing having a slit therein, a spindle rotatably 45 mounted within said casing, means outside the casing for revolving the spindle, a flexible lead strip wound around the spindle and having an end portion made resilient so that, as the spindle is turned, the said end will snap out of said slit. 50

2. A device in accordance with claim 1 wherein the resilient end of the lead strip is made curved.

3. In a stamp magazine, a tubular casing having a slit therein, a spindle rotatably 55 mounted within said casing, means outside the casing for revolving the spindle, a flexible lead strip wound around the spindle and having an end portion stiffened so that as the bobbin is turned the same end will snap out of said slit. 60

In testimony whereof, I have signed my name to this specification this 31st day of December, 1928.
